UNITED STATES PATENT OFFICE

WALTER G. FURLONG AND KENNEDY H. CRUMRINE, OF CLEVELAND, OHIO, ASSIGNORS
TO THE NATIONAL ACME COMPANY, OF CLEVELAND, OHIO, A CORPORATION OF
OHIO

THREADING DIE

Application filed December 17, 1926. Serial No. 155,374.

This invention relates to automatic threading dies, the object thereof being to provide an improved die of simple construction by means of which the chasers can be brought up closer to the shoulder of the work and quickly released, the present die being an improvement upon that shown and described in Patent No. 1,474,179 dated November 13, 1923, and owned by The National Acme Company, the assignee of the present improvement.

The present improved die very much simplifies the die shown and described in the patent referred to in that it entirely eliminates a number of parts necessary in that die including the ring 41 of that patent. In other words, instead of the two rings 36 and 41 of that patent but one is necessary in the present die and in the present improvement the operating lever or handle is connected directly with the die body instead of to the ring 41 as in the prior patent, so that the lever operates directly on the die body instead of in a ring carried on the shank of the die body. This change of construction, aside from eliminating certain parts, also permits the adjusting ring to be carried within the cap or housing instead of in the rear thereof as in said patent, which thus permits the adjusting screws to be located in the heavy portion or back wall of the cap shell or housing, instead of, as in the patent, in the thin portion of such cap. In the present improvement the construction is such that the instant the die body is drawn forward to a position to permit the dies or chasers to open freely, the die cap or housing is, simultaneously with this opening movement of the dies or chasers, forced rearwardly, thus making the opening or closing of the dies exceptionally quick or rapid. Another of the improved features of the present die is the cooperating tapered or beveled portions of the forward end of the body shank and the opening or bore of the body whereby the packing of the chips is prevented so as to eliminate any interference with the proper free end motion of the die body relative to the shank, whereas in the patent aforesaid

the shank of the body is telescoped on to the spindle.

In the patent aforesaid, the die body is provided with an integral shank overlapping the forward end of the spindle. In the present improved die the body and its shank are separable, the latter extending into the body and being resiliently connected therewith, thereby to permit the body to have an endwise shiftable movement relative to its shank, which construction eliminates certain parts necessary in the patented die, while at the same time it prevents the packing of the chips thus permitting the thorough oil washing of the body.

Other objects of the invention will appear in the following description thereof.

In the drawings accompanying and forming a part of this specification, Fig. 1 is a front end view of this improved die with the chasers in their working position. Fig. 2 is a side partly longitudinal sectional view of this improved die also illustrating the chasers in their closed position, the dotted lines illustrating the movement of the handle or lever when the chasers are opened. Fig. 3 is a longitudinal sectional view of this improved die, showing the chasers in position in readiness to be released. Fig. 4 is a similar view to that shown in Fig. 3 with the chasers in their fully opened position and the die cap pushed back. Fig. 5 is a cross sectional view through a part of the die illustrating a portion of the adjustable ring and the means for adjusting it and thereby the chasers. Fig. 6 is a perspective view of the die body. Fig. 7 is a perspective view of the die body shank. Fig. 8 is a perspective view of the retaining ring for securing the die shank to the body. Fig. 9 is a perspective view of the adjusting ring which is located within the shell or housing. Fig. 10 is a perspective view of the die cap or shell or housing. Fig. 11 is a perspective view of the lever fulcrum bracket. Fig. 12 is a perspective view of the lever or handle for closing the chasers. Fig. 13 is a perspective view of one of the chasers and its fastening screw. Fig. 14 is a perspective view of one of the chaser blocks or plates and the spring for opening the chaser.

Fig. 15 is a longitudinal sectional view of the die head illustrating the position of the body and cap or housing when the chasers are in their closed position. Fig. 16 is a similar view illustrating the position of the die body or shell or cap when the chasers are in position to be released and Fig. 17 is a similar view illustrating the position of the die body and its cap or housing when the chasers have been fully released.

Similar characters of reference in the drawings designate corresponding parts in the several views.

Before explaining in detail the present improvement and mode of operation thereof, we desire to have it understood that the invention is not limited to the details of construction and arrangement of parts which are illustrated in the accompanying drawings, since the invention is capable of other embodiments, and that the phraseology which we employ is for the purpose of description and not of limitation.

This improved threading tool or die comprises a die cap shell or housing 1 having suitable central bores for receiving the die body 2 and the die shank 3. This die body 2 is provided in the rear thereof with a counter-bored opening for receiving the projecting or spigot end 4 of the die shank 3, and this projecting end 4 of the die shank is interiorly beveled as at 5, and the counter-bore or opening of the body is also beveled as at 6, and these cooperating beveled portions prevent the chips from packing between the die body 2 and the die shank 3 and therefore permit a free end motion of the die body relatively to the shank in the manner hereinafter described. The die body is provided with a plurality of chaser receiving slots or recesses shown herein as four in number for positioning and guiding the threading dies or chasers 7 and their plates or blocks 8. Each of these recesses is of T-shaped form, the forward part thereof 9 receiving the chasers and the rear part thereof 10 receiving the chaser blocks or plates 8, to which the chasers are secured by suitable screws 11. Each of the chaser blocks or plates 8 is provided with a projecting pin 12 extending into its chaser and into a slot or opening 13 in the wall of the die body for properly positioning and guiding the chaser, and between one end of each pin 12 and the bottom wall of each slot 13 is located a spring 14 effective to open or release the chaser at the proper time. Each of the chasers is provided with what is usually designated as a land surface 15, curved circumferentially of the die but straight in the direction of the depth of the die or chaser for cooperation with the cam formed stations or portions 16 on the die shell, whereby on the relative rotation of the body and die shell the chasers are adjusted to make the proper cut. In the rear of this land surface the

chasers are provided with an inclined or cam surface 17 operative at the proper time to force or push the shell rearwardly thereby to permit the chasers to be opened to their full extent through the medium of their springs 14 and so release the work. The die body 2 is provided with a pair of radially extending alined recesses 18 for the reception of a pair of opposed radially extending driving lugs 19 integral with the die shank 3. These driving lugs are retained in place by a retaining ring 20 secured to the rear of the die body by suitable screws. The recesses 18 are of such depth relative to the driving lugs 19 as to form a clearance space 21 between the driving lugs and the retaining ring 20 when the die is in its normal assembled condition.

The driving lugs 19 are provided with openings 22 for the reception of springs 23, the opposite ends of which engage the retaining ring 20. These springs 23 maintain the die body 2 in fixed end relation relatively to the driving lugs 19. That is to say, they hold the driving lugs in engagement with the front walls of the recesses 18, see Fig. 15, while permitting forward movement of the die body relatively to these driving lugs 19 and its shank 3 owing to the clearance space 21, thereby to properly position the threading dies or chasers 7 for opening movement to release the work.

The die body 2 is provided with a slot 24 for receiving the end of a lever 25 shown in the present instance as a handle lever, by means of which, in the form of die shown, the chasers are reset. The die cap or housing 1 is provided with a fulcrum bracket 26, secured thereto by suitable screws 27; and this bracket 26 is provided with a pin 28 for properly supporting the lever 25. When this lever 25 is pushed forward by hand or by striking a stop connected to the machine, the body carrying the chasers will be returned within this cap or housing and the chasers thereby closed, this being accomplished on the return stroke of the spindle or turret slide carrying the threading die.

In the present improvement it will be observed that this lever projects directly into the die body and it is not therefore connected with a ring mounted on the body shank as in the patent hereinbefore referred to.

In order properly to adjust the threading dies or chasers a float or adjusting ring 29 is provided, this ring having a fixed guide pin 30 in position to project through an opening 31 in the retaining ring and into an opening in the rear wall of the die body. This adjusting ring 29 is held against endwise movement in the die cap by a shoulder screw 32 projecting through a shouldered arcuate slot 33 formed in the adjusting ring. This arcuate slot permits rotary or circumferential movement of the adjusting ring and the die body 2, since the two are shiftably connected to

gether by the pin 30 and this circumferential movement is obtained by a pair of adjusting screws 34 carried in suitable threaded openings in the die cap. These adjusting screws 5 engage lugs 35 integrally secured to the rear wall of the adjusting ring and these lugs project into arcuate recesses 36 located in the rear wall of the die cap in position to be engaged by the ends of the adjusting screws 34. By 10 adjusting one screw 34 right hand or inward to push against its lug 35 and the other screw 34 outward or left hand from its cooperating lug 35, the adjustable ring 29 and the die body 2, owing to the connecting pin 30, will be rotated relatively to the cap or housing. This 15 rotary movement of the die body causes the threading dies to move either toward the center line of the work spindle or outward or from the center line of such work spindle according to the adjustment desired, owing to 20 the four cam faces or stations 16 hereinbefore referred to on the die cap, see Fig. 10, which engage the land surfaces 15 of the chasers 7, there being one cam face or station 16 on the 25 die cap for each chaser. By this means the threading dies or chasers 7 are adjusted for the proper thread pitch and the proper diameter of the work or part to be threaded. The 30 radial adjustment of the threading dies is made or controlled by a suitable fractional graduation 37 located on the adjusting ring 29, the die cap having a bevel face opening 38 therefor. The beveled portion of this opening 38 is provided with an index line 39 and 35 the adjusting ring 29 is graduated on its periphery for a length equal to the maximum radial movement required for a full range of adjustment of the threading dies 7 in either direction. The index line on the die cap and 40 the graduations or divisions on the adjustable ring permit the proper adjustment of the threading dies and control the same.

In practice the threading die is mounted on a spindle or turret slide of a machine used 45 for threading and the threading die is started on to its work on the forward movement of this spindle or turret slide. After the threading die is started on to the work, the revolving spindle carrying the work automatically pulls 50 the threading die and the machine spindle or turret slide forward equal to the length of the thread desired on the work less the travel required of the threading die for positioning to release the work. This forward travel of 55 the die and its turret slide continues until the turret slide strikes a suitable stop on the machine which thereupon retards or holds the die carrying spindle against any further travel. This stop is stationed on the machine 60 in a fixed adjusted relation to the threading die and permits further end travel of the die body 2 by means of the revolving work spindle which end travel is sufficient to close the clearance space 21 and which space is equal to 65 the land surface 15 on the top of the thread-

ing dies or chasers. This forward travel of the die body 2 after the machine spindle or turret slide is stopped by means of the stop provided on the machine for that purpose, permits the threading dies or chasers to run 70 close up to the shoulder of the work that has been threaded and also positions the threading dies or chasers in readiness to release the work, see Fig. 3. By bringing the juncture point of the land surface of the chasers and the inclined cam surface thereof in juxtaposition to the forward inner edge of the cap or housing, see Fig. 3, the chaser springs will move the chasers outwardly to open them at which time the inclined cam surfaces of the chasers will force or push back the cap or housing, see Fig. 4, thereby permitting the chasers to be fully opened by their springs 14 cooperating with the pins 12. On this opening movement of the chasers the die body 2 is, 75 as just stated, forced rearwardly or away from the shoulder on the work by the cam surfaces 17. Fig. 15 shows the clearance space or gap 21 before the die body has been pulled forward. Fig. 16 shows the clearance 80 or gap 21^a between the die body 2 and the driving lugs 19 when the threading dies or chasers are in position in readiness to release the work, while Fig. 17 shows the clearance space or gap 21 when the die body again assumes its original position in relation to its 85 die shank 3 and its lugs 19.

When the die carrying spindle or turret slide is ready for its next forward movement or threading operation, the threading dies are 90 closed by means of the lever 25 by shifting this lever from its dotted line position into its full line position.

When it is desired to use the die with a revolving spindle, the cap is provided with a 95 grooved collar at the rear end thereof for shifting the cap or housing to close the chasers, as shown at 26 (Fig. 6) of the said Patent No. 1,474,179.

From the foregoing it will be observed that 100 the die comprises a comparatively few number of parts and is extremely simple in its construction and assemblage and consequently it may easily be taken apart and cleaned, this being accomplished by merely removing two 105 screws holding the handled lever in place whereby the die body with its shank attached can be slipped out of the cap so that the cap and the die body may be thoroughly cleaned, this requiring but a few minutes. The parts 110 can readily be reassembled without interfering with the cutting size of the chasers since the adjusting screws need not be touched.

One of the principal advantages of this improved die is that the die body can be pulled 115 back away from the work at the instant of opening of the chasers, thus permitting close-to-the-shoulder threading and accurate cutting of short threads. The chasers can be adjusted to the proper size of work quickly by 120

means of a screw driver without removing the die from its holder since the adjusting screws are located in the periphery of the cap and are easily accessible.

5 Furthermore the present construction enables all parts of the die to be properly hardened and ground and permits the free flow of oil through the body of the die and its shank which is tubular, thereby to wash away the 10 chips from the tool, the collecting of which is prevented by the beveled formed parts of the die body and spigot end of the shank.

When the body is pulled forward to permit the chasers to be opened, the cap is prevented 15 from forward movement therewith by a pair of stops or lugs 40 carried by the shank 3 and engaged by the adjusting ring carried by the cap, thus limiting the forward movement of the cap and permitting the body to be drawn 20 forward the required distance to release the chasers.

These stops 40 are shown formed as part of the driving lugs 19, being located at the rear thereof, thus providing a stepped formation 25 near the end of the shank.

It is to be understood that by describing in detail herein any particular form, structure or arrangement, it is not intended to limit the invention beyond the terms of the 30 several claims or the requirements of the prior art.

Having thus explained the nature of our said invention and described a way of constructing and using the same, although without attempting to set forth all of the forms in which it may be made, or all of the modes of its use, we claim:

1. A threading die comprising a cap having a pair of arcuate recesses in its rear wall, a die body within said cap and provided with shiftable chasers, an adjusting member within said cap and having rearwardly projecting lugs extending into said arcuate recesses and a forwardly projecting 45 pin extending into the body of the die, and adjusting screws projecting through the rear wall of the cap to engage said lugs for adjusting the chasers.

2. A threading die comprising a cap having a pair of arcuate recesses in its rear wall, a die body within said cap and provided with chasers and with a pair of radially located recesses in its rear wall, a shank having a pair of radially projecting lugs fitting the recesses of the die body and having a depth less than the depth of the recesses of said die body, a retaining ring secured to the body, springs between said retaining ring and the shank lugs, an adjusting ring fitting said shank and located within the cap and connected thereto for circumferential movement, said ring having a pair of rearwardly extending lugs fitting the arcuate recesses of the cap and also having a forwardly projecting pin extending through the retaining ring and into the body of the die, a pair of adjusting screws projecting through the rear wall of the cap to engage the lugs of the adjusting ring thereby to adjust the chasers, and a lever fulcrumed on the cap and projecting directly into the die body for closing the die.

3. A threading die comprising a cap having a pair of arcuate recesses in its rear wall, a die body within said cap and provided with chasers and with a pair of radially located recesses in its rear wall, a shank having a pair of radially projecting lugs fitting the recesses of the die body and having a depth less than the depth of the recesses of said die body, a retaining ring secured to the body, springs between said retaining ring and the shank lugs, an adjusting ring fitting thereby to adjust the chasers.

3. A threading die comprising a cap having a pair of arcuate recesses in its rear wall, a die body within said cap and provided with chasers and with a pair of radially located recesses in its rear wall, a shank having a pair of radially projecting lugs fitting the recesses of the die body and having a depth less than the depth of the recesses of said die body, a retaining ring secured to the body, springs between said retaining ring and the shank lugs, an adjusting ring fitting said shank and located within the cap and connected thereto for circumferential movement, said ring having a pair of rearwardly extending lugs fitting the arcuate recesses of the cap and also having a forwardly projecting pin extending through the retaining ring and into the body of the die, and a pair of adjusting screws projecting through the rear wall of the cap to engage the lugs of the adjusting ring thereby to adjust the chasers, said body having a beveled counter-bore and said shank having a beveled forward end in juxtaposition thereto.

4. A threading die comprising a cap having a pair of arcuate recesses in its rear wall, a die body within said cap and provided with chasers and with a pair of radially located recesses in its rear wall, a shank having a pair of radially projecting lugs fitting the recesses of the die body and having a depth less than the depth of the recesses of said die body, a retaining ring secured to the body, springs between said retaining ring and the shank lugs, an adjusting ring fitting said shank and located within the cap and connected thereto for circumferential movement, said ring having a pair of rearwardly extending lugs fitting the arcuate recesses of the cap and also having a forwardly projecting pin extending through the retaining ring and into the body of the die, a pair of adjusting screws projecting through the rear wall of the cap to engage the lugs of the adjusting ring thereby to adjust the chasers, and a lever fulcrumed on the cap and projecting directly into the die body for closing the die.

5. A threading die comprising a cap having a pair of arcuate recesses in its rear wall, a die body within said cap and provided with chasers and with a pair of radially located recesses in its rear wall, a shank having a pair of radially projecting lugs fitting the recesses of the die body and having a depth less than the depth of the recesses of said die body, a retaining ring secured to the body, springs between said retaining ring and the shank lugs, an adjusting ring fitting

- 5 said shank and located within the cap and connected thereto for circumferential movement, said ring having a pair of rearwardly extending lugs fitting the arcuate recesses of the cap and also having a forwardly projecting pin extending through the retaining ring and into the body of the die, a pair of adjusting screws projecting through the rear wall of the cap to engage the lugs of the adjusting ring thereby to adjust the chasers, 10 said body having a beveled counter-bore and said shank having a beveled forward end in juxtaposition thereto, and a lever fulcrumed on the cap and projecting directly into the die body for closing the die. 15
6. A threading die comprising a cap, a die body therein corresponding substantially to the interior diameter of the cap and provided with shiftable chasers, a shank resiliently connected with the die body to permit the body to have endwise movement relatively to the shank, an operating lever fulcrumed to the cap and projecting directly into the die body, an adjusting ring carried within 20 the cap and having connection with the die body to permit endwise movement thereof, and means carried by said cap for adjusting said ring and thereby the die body to adjust the chasers. 25
7. A threading die comprising a cap, a die body therein corresponding substantially to the interior diameter of the cap and provided with shiftable chasers, a shank resiliently connected with the die body to permit the body 30 to have endwise movement relatively to the shank, an operating lever fulcrumed to the cap and projecting directly into the die body, an adjusting ring carried within the cap and having connection with the die body to permit endwise movement thereof, and means carried by said cap for adjusting said ring and thereby the die body to adjust the chasers. 35
8. A threading die comprising a cap, a die body therein provided with a plurality of shiftable chasers, a shank projecting directly into said body and resiliently connected therewith whereby the body has endwise movement relatively to said shank, said cap having a plurality of arcuate recesses in its rear 40 wall, an adjusting ring located within said cap and having rearwardly projecting lugs extending into said recesses and a forwardly projecting pin extending into the die body, and means carried by the rear wall of the cap for engaging said lugs to adjust the chasers. 45
9. A threading die comprising a cap, a die body therein provided with a plurality of shiftable chasers, a shank projecting directly 50 into said body and resiliently connected therewith whereby the body has endwise movement relatively to said shank, said cap having a plurality of arcuate recesses in its rear wall, an adjusting ring located within said cap and having rearwardly projecting lugs extending into said recesses and a forwardly projecting pin extending into the die body, and means carried by the rear wall of the cap for engaging said lugs to adjust the chasers. 55
10. A threading die comprising a cap, a die body shiftable endwise therein and provided with chasers, a die shank having driving means directly and resiliently connected with the body whereby the body has endwise movement relatively to the shank, and means rigid with the shank for engaging and limiting the forward movement of the cap during the forward movement of the body. 60
11. A threading die comprising a cap, a die body therein provided with a plurality of shiftable chasers, a shank projecting directly into said body and resiliently connected therewith whereby the body has endwise movement relatively to said shank, and means for preventing the forward movement of the cap during the forward movement of the body and comprising a stop rigid with the shank and engaging a part carried by the cap. 65
12. A threading die comprising a cap, a chaser-carrying die body endwise shiftable in the cap, a die shank projecting directly into the body and having interlocking driving means at its front end within the body, said driving means comprising a radial lug and a radial recess, one carried by the shank and the other by the body, the lug having less depth than the depth of the recess. 70
13. A threading die comprising a cap, a chaser-carrying die body shiftable endwise therein and a die shank having interlocking driving means at its front end within the body and resiliently connected with the body in the rear of said driving means, whereby the body has endwise movement relatively to the shank, said driving means comprising a radially projecting lug and a radial recess, one carried by the body and the other by the shank. 75
14. A threading die comprising a cap, a chaser-carrying die body shiftable endwise therein and a die shank having driving means at its front end within the body and resiliently connected with the body in the rear of said driving means, whereby the body has endwise movement relatively to the shank, said driving means comprising a radially projecting lug and a radial recess, one carried by the body and the other by the shank, said recess having greater depth than the depth of the lug. 80
15. A threading die comprising a cap, a chaser-carrying die body shiftable endwise 85

- in the cap, a die shank projecting directly into the body and having driving means at its front end within the body, and comprising a pair of radially projecting lugs carried by the shank and a pair of radial recesses carried by the body for the reception of said lugs, the depth of said recesses being greater than the depth of the lugs, a retaining ring carried by the body in the rear of the lugs, and 10 springs between the retaining ring and the lugs.
16. A threading die comprising a cap having a pair of arcuate recesses in its rear wall, a chaser-carrying die body within the cap and having means for receiving die-shank driving means resiliently co-operating therewith to drive the die body, said driving means including a die shank, an adjustable member within the cap and connected with the body 15 and having rearwardly-projecting lugs, extending into said arcuate recesses of the cap, and adjustable screws projecting through the rear wall of the cap for engaging said lugs thereby to adjust the chasers.
17. A threading die comprising a cap, a chaser-carrying die body shiftable endwise therein, a die shank having driving means at its front end within the body and resiliently connected with the body in the rear of said 20 driving means, whereby the body has endwise movement relatively to the shank, said body and shank having, one, a radially projecting lug and, the other, a radial recess for the reception of said lug, an adjusting ring carried 25 within the cap and having connection with the die body to permit endwise movement of the body, and means carried by said cap for adjusting said ring and thereby the die body to adjust the chaser, said chaser and cap having, 30 one, circumferential cam surfaces and, the other, depthwise-located cam surfaces.
18. A threading die comprising a cap, a die body therein provided with a plurality of shiftable chasers, and a shank projecting directly into said body and having radially extending lug interlocking driving means within the body at the extreme forward end of the shank and resiliently connected therewith in the rear of said driving means, whereby the 35 body has endwise movement relatively to said shank.
19. A threading die comprising a cap, a die body therein provided with a plurality of shiftable chasers, and a shank projecting directly into said body and having radially extending lug interlocking driving means within the body at the extreme forward end of the shank and resiliently connected therewith in the rear of said driving means, whereby the 40 body has endwise movement relatively to said shank, said body and shank having juxtaposed beveled surfaces.
20. A threading die comprising a cap, a chaser-carrying die body shiftable endwise therein, a die shank having interlock- 45
- ing driving means at its front end within the body and resiliently connected with the body in the rear of said driving means, whereby the body has endwise movement relatively to the shank, said driving means comprising a radially projecting lug and a radial recess for the reception of said lug, means for adjusting the chasers, and means fulcrumed on the cap and directly engaging the body for closing the chasers.
21. A threading die comprising a cap, a chaser-carrying die body shiftable endwise therein, a die shank having driving means at its front end within the body and resiliently connected with the body in the rear of said driving means, whereby the body has endwise movement relatively to the shank, said driving means comprising a radially projecting lug and a radial recess, one carried by the body and the other by the shank, and means carried by the die shank for limiting the forward movement of the cap during the forward movement of the body.
22. A threading die comprising a cap, a chaser-carrying body shiftable endwise therein, a shank, said cap and shank having, one, a radial recess and, the other, a radial driving lug having a sliding fit in said recess and having a depth less than that of the recess, a retaining ring secured to the rear of the body in the rear of said lug and through which the shank projects, and a spring between said lug and retaining ring, whereby the body and shank are directly and resiliently connected to permit the body to have endwise movement only relatively to the shank.
23. A threading die comprising a cap, a chaser-carrying body shiftable endwise therein, a shank, said cap and shank having, one, a radial recess and, the other, a radial driving lug having a sliding fit in said recess and having a depth less than that of the recess, a retaining ring secured to the rear of the body in the rear of said lug and through which the shank projects, a spring between said lug and retaining ring, whereby the body and shank are directly and resiliently connected to permit the body to have endwise movement only relatively to the shank, and a chaser-adjusting ring on the shank in the rear of said retaining ring.
24. A threading die comprising a cap, a chaser-carrying body shiftable endwise therein, a shank, said cap and shank having, one, a radial recess and, the other, a radial driving lug, having a sliding fit in said recess and having a depth less than that of the recess, a retaining ring secured to the rear of the body in the rear of said lug and through which the shank projects, a spring between said lug and retaining ring, whereby the body and shank are directly and resiliently connected to permit the body to have endwise movement only relatively to the shank, and a chaser-adjusting ring on the shank in the rear of said retaining ring.

rear of said retaining ring, said cap encircling said shank and enclosing the body, driving lugs, retaining ring and adjusting ring.

25. A threading die comprising a cap, a chaser-carrying body shiftable endwise therein, a shank, said cap and shank having, one, a radial recess and, the other, a radial driving lug having a sliding fit in said recess and having a depth less than that of the recess, a retaining ring secured to the rear of the body in the rear of said lug and through which the shank projects, a spring between said lug and retaining ring, whereby the body and shank are directly and resiliently connected to permit the body to have endwise movement only relatively to the shank, and a chaser-adjusting ring on the shank in the rear of said retaining ring, said body and the 20 front end of the shank having co-operating beveled surfaces in juxtaposition.

Signed at Cleveland, Ohio, this 13th day of December, 1926.
